George L. Birch,

UNITED STATES PATENT OFFICE.

GEORGE L. BIRCH, OF WILTON, KENTUCKY.

LUBRICATING-AXLE.

1,216,768.

Specification of Letters Patent.

Patented Feb. 20, 1917.

Application filed October 1, 1913. Serial No. 792,837.

To all whom it may concern:

Be it known that I, GEORGE L. BIRCH, a citizen of the United States, residing at Wilton, in the county of Knox and State of Kentucky, have invented certain new and useful Improvements in Lubricating-Axes, of which the following is a specification.

This invention relates to trolley harps, and more particularly to a novel and efficient 10 lubricating means therefor.

An object of this invention is to associate with the harp suitable lubricating means so as to facilitate the rotation of the trolley wheel, means being likewise provided to decrease the wear on the harp and at the same 15 time providing a device comprising but comparatively few parts which may be readily associated for performing the desired function.

Other objects as well as the nature, characteristic features and scope of my invention will be more readily understood from the following description taken in connection 20 with the accompanying drawings and pointed out in the claim forming a part of this specification.

Referring to the drawings:—

Figure 1 is a side elevation of a harp constructed in accordance with my invention; 25 Fig. 2 is a sectional view taken on the line 2—2 of Fig. 1; and

Fig. 3 is a perspective view of the improved wear plate used in the present invention.

In the drawings wherein is illustrated the preferred embodiment of the present invention, my improved trolley harp is preferably of a substantially U-shaped configuration as indicated at 5 and shown to advantage in Fig. 2, the one end of the arm 6 of the body portion being enlarged as at 7 and provided with a transverse opening therethrough which communicates with a cut-out portion 8 on the outer face thereof.

The opposite arm 9 of the body portion 5 is preferably enlarged and provided with a longitudinally extending lubricating chamber or bore 10 the lower end of which is preferably screw-threaded as indicated at 11, the upper end thereof communicating with a transverse opening 12, and said transverse opening communicating on the outer end thereof with a cut-out portion 13.

Adjustably mounted in the chamber 10, 55 is a screw-bolt 14 the external threads thereof being engaged with the internal threads

11 of the arm 9, said screw-bolt being provided in order to dispense the contents of said chamber 10 through the upper end thereof and into the transverse opening 12 for a purpose which will presently appear. In order to prevent wear on the bottom of the trolley harp occasioned by the contacting thereof with the plate 15 on the trolley pole, I have provided a simple and efficient 65 wear plate 16 which is interposed between the pole plate 15 and the lower face of the trolley harp, the marginal edge thereof conforming to the configuration of the marginal edges of said harp and said pole plate, 70 said wear plate being provided with an opening 17 therein through which the swivel bolt 18 passes so as to engage the trolley plate therewith, said swivel bolt extending upwardly through the harp and having engagement therewith, the lower end of said bolt provided with an eye through which is engaged the trolley cable, said plate being provided with a second opening or aperture 18 which is of a diameter smaller than that 75 of the opening 17 and has the one end thereof preferably tapered, in order that the rivet or screw which is associated therewith, may be countersunk so as to allow for the free movement of the harp on the trolley 80 pole.

Mounted in proximity to the upper end of the trolley harp 5, is an axle 19 which is preferably hollow as indicated at 20, for a portion of its length, said hollow portion 90 having a pair of apertures 21 and 22 opening therewith, the opening 22 communicating with the lubricating chamber 10 in the arm 9, while the opening 21 is formed approximately midway the ends of said axle, 95 and between the arms 6 and 9, so as to dispense the contents of the chamber 10 therethrough and on the inner periphery of the trolley wheel which is mounted on said axle. In order to fixedly secure said axle in engagement with the arms 6 and 9, an opening 100 is formed adjacent each end of said axle, said openings being in engagement with cotter pins 23, said cotter pins lying in the cut-out portions 8 and 13, so as to prevent 105 the movement of the axle in the transverse openings which are formed in proximity to the upper end of the arms 6 and 9.

In operation the chamber 10 is filled with a lubricant, preferably a solid lubricant being used, and when it is desired to dispense 110 the same through the aperture 22 and into

the bore 20 of the axle 19, pressure is exerted on the screw-bolt 14, which as is evident normally lies in the lower end of said arm, and is actuated by turning the same so as to cause the contents of said chamber to be dispensed therethrough and into said axle, so as to lubricate the trolley wheel which is mounted thereon. It is of course obvious that after the chamber 10 has been packed with a lubricant, that one revolution of the screw-bolt 14 will be sufficient to lubricate the trolley wheel which is mounted on the axle 19, for a certain length of time.

It will be understood that the above description and accompanying drawings comprehend only the general and preferred embodiment of my invention and that various minor changes in details of construction, proportion and arrangement of the parts may be made within the scope of the appended claim and without sacrificing any of the advantages of my invention.

Having thus fully described my invention what I claim as new and desire to secure by Letters Patent is:

A trolley harp including a substantially U-shaped body, one of the arms of said body being enlarged transversely and provided with a longitudinally extending lubricant chamber, an axle having its ends journaled through the arms of said body and arranged

to project to each side thereof, said axle provided with a centrally arranged longitudinally extending compartment terminating short of the ends thereof, said axle being passed through said lubricant chamber, and provided with an aperture communicating with said compartment and with said chamber, said axle being further provided with an egress opening to communicate with said compartment substantially intermediate its ends whereby the lubricant may be supplied to the trolley wheel, the arms of said body portion provided with receiving grooves adjacent the ends of said axle, cotter pins to be passed through the ends of said axle beyond the outer faces of said arms to lie in said grooves whereby said axle will be held against turning movement, said axle being removable from either side of said arms, and a force feed member to be removably mounted in said lubricant chamber to force the lubricant to said compartment by way of said first mentioned aperture, as and for the purpose specified.

In testimony whereof I affix my signature in presence of two witnesses.

GEORGE L. BIRCH.
